SHOE SEWING MACHINE

Fred Ashworth, Wenham, Mass., assignor to
United Shoe Machinery Corporation, Flemington, N. J., a corporation of New Jersey

Application January 7, 1950, Serial No. 137,343

9 Claims. (Cl. 112—37)

1 The present invention relates to shoe outsole sewing machines and more particularly to improvements in work supports for machines of the type disclosed in United States Letters Patent No. 2,271,611, granted February 3, 1942, upon application of the present inventor and Carl F. Whitaker for sewing outsoles to welts of Goodyear welt shoes with even edged seams having lengths of thread exposed on the surface of the welt arranged in a desirable accurately alined relationship.

The machine of the patent above referred to is a lock-stitch welt shoe sole sewing machine in which the work is fed while clamped and the stitch forming devices of which are so arranged that thread lengths exposed on the welt in succeeding stitches frequently are disposed out of line with each other or in zigzag relationship. With the exposed thread lengths of a seam disposed in zigzag relationship, the appearance produced does not always conform with other elements of style and design in a particular type of shoe being manufactured. For this reason it is preferable to insert stitches with the exposed thread lengths arranged in a narrow continuous straight line formation.

The principal object of the present invention is to provide a clamp feed shoe outsole sewing machine in which the desired results of seam formation may be obtained without affecting detrimentally any of the essential characteristics of the seam, or requiring complicated and difficult adjustments to be made by the operator. Other objects are to improve the work support of a shoe outsole sewing machine in a manner to insure insertion of a seam with the thread lengths exposed on at least one side of the work in accurate alinement from one stitch to another.

In sewing the outseam of a Goodyear welt shoe, the shoe is presented to the sewing machine in an upside-down position with the welt engaging the work support. A machine of the type disclosed in the patent has a hook needle and the thread is laid in the needle hook by cooperative action of a looper and a thread finger. During the retracting stroke of the threaded needle a length of thread engaged by the thread finger is released and is drawn toward the welt. After being released by the thread finger, slack thread exists between the last formed stitch in the work and the stitch being formed. Accordingly, there is no accurate control of its movement laterally of the seam line while being drawn against the welt. Without lateral control of the thread movement there is corresponding lack of uni-

form thread placement and appearance in the finished seam.

5 In accordance with the present invention a hook needle clamp feed outsole sewing machine is provided in which the work feeding work support has a needle receiving opening formed with a restriction of a width sufficient to receive the thread but insufficient to admit the needle, at that end toward which the work is fed to limit movement laterally of the seam line of slack thread released by the thread finger and drawn through the work by the needle. By limiting the movement of the thread laterally of the seam line, accurate placement of the thread is insured and the thread lengths exposed on the surface of the welt when sewing an outsole are readily maintained in alinement with great uniformity. Preferably, the restriction in the needle opening of the work support constitutes a continuation **10** of the forward surface of the needle opening and the rearward surface of the restriction is spaced from the rearward surface of the needle opening. In this way, greater clearances are obtainable between the outer edge of the work support and the bulging surface of a shoe upper being sewn and a still more effective result in alinement is obtained.

15 These and other features of the invention as hereinafter described and claimed will be apparent to those skilled in the art from the following detail specification taken in connection with the accompanying drawings in which,

20 Fig. 1 is a detail plan view of the work clamping and feeding work support and its actuating mechanism in a shoe outsole sewing machine embodying the features of the invention;

25 Fig. 2 is an enlarged plan view of the forward portion of a work support embodying the invention together with a portion of a welt shoe being sewn, showing the relationship of slack needle thread as it is drawn against the welt;

30 Fig. 3 is a sectional view taken along the line III—III of Fig. 2;

35 Fig. 4 is a further sectional view taken along the line IV—IV of Fig. 3;

40 Fig. 5 is a detail view of the work engaging surface portion of the work support;

45 Fig. 6 is a view in left side elevation of the work support portion shown in Fig. 5;

50 Fig. 7 is a plan view of the work engaging portion of a work support according to the present invention, in a somewhat modified form;

55 Fig. 8 is a sectional view of the work support portion shown in Fig. 6 taken along the line VIII—VIII;

Fig. 9 is a partial view in left side elevation of the modified work support shown in Fig. 7;

Fig. 10 is a plan view of a portion of a welt shoe welt side up showing the results obtained by the use of the machine of the present invention; and

Fig. 11 is a similar plan view of a welt shoe sewn by a machine such as that disclosed in the prior patent above referred to.

The illustrated machine is the same in construction and mode of operation in all of its principal operating parts as that of the machine in the above mentioned patent and in United States Letters Patent No. 2,397,588 granted April 2, 1946, upon application of the same inventors named in the first-mentioned patent.

Referring more particularly to Fig. 3, of the present drawings the machine is provided with a curved hook needle 12, a curved awl 14 of square cross section, a needle looper 16, a thread finger 18, a loop spreader 20, a work support 22 having a downwardly and rearwardly swept shank and an elongated needle and awl receiving opening, and a presser foot 24 at the side of the work with the needle. The machine is of the clamp feed type in which the presser foot clamps the work against the work support and moves relatively to the needle and awl a stitch length during each sewing cycle. Thereafter, the awl penetrates the work and the presser foot releases the work so that the presser foot and work support may be backfed with relation to the work in preparation for a new work feeding movement, the awl retaining the work against retrograde movement during the back feeding movement of the presser foot and work support.

The work support and presser foot are mounted upon an oscillating feed carriage 26 secured to an inclined pivot shaft 28 as more fully described in Patent No. 2,397,588. For actuating the presser foot and work support in the direction of workfeed, the carriage has a rearwardly extending arm connected by a link 30, in turn connected to the central joint of a pair of toggle links 32 and 34, the link 32 being pivotally mounted on a yoke 36 and the link 34 being connected to one arm of a cam lever 38 actuated in turn by a cam 40 on a main sewing shaft 42. The shape of the cam 40 is such that the work support and presser foot exert a relatively slow rearward pull on the work during each feeding movement and a relatively quick forward thrust against the work during each back feeding movement. Such an arrangement is of an advantage in maintaining the work accurately in position without possibility of accidental release during operation of the machine.

The awl 14 is sharpened by forming bevel faces, one of which is illustrated at 42 in Fig. 3 to form a cutting edge extending diagonally of the seam line from the right-hand forward corner of its cross section to the left-hand rear corner, thus enabling the awl to produce an angular cut in the work during its penetrating movement. The cuts formed by the awl are illustrated at 44 in Fig. 2 extending at an angle of approximately 45° to the seam line. After perforating the work, the awl is withdrawn and the needle enters the awl perforation. The needle is actuated to emerge from the lower surface of the work through the needle receiving opening, indicated at 46, intersecting a work engaging surface 48 on the work support and extending rearwardly in the direction of the rearwardly swept shank. The left end of the work engaging surface 48 is

somewhat higher than the right end with a raised portion for causing the pressure exerted on the work to be centralized at the left side of the needle opening.

When the needle emerges from the lower surface of the work, the looper 16 is actuated to lay the thread in the open hook of the needle. Before laying the thread in the needle hook, a measured length is carried about the thread finger 18 to provide slack thread between the last formed stitch in the work and the needle during its retracting stroke. As soon as the needle begins to retract, the measured thread is disengaged from the thread finger as shown in Fig. 3. 10 This measured length of thread is momentarily left slack during the continued retracting movement of the needle and the entry of the loop spreader 20 into the needle loop. Unless means is otherwise provided, this slack length of thread will move erratically forwardly or rearwardly along the diagonal awl cuts until it eventually is tightened against the undersurface of the work, which in a welt shoe is the outsole attaching welt.

25 A portion of a welt shoe being operated upon is indicated in Figs. 3 and 4, the outsole being shown at 50, the welt at 52, the upper at 54 and a last on which the shoe is formed at 56. The seam connecting the outsole and welt is a lock-stitch seam consisting of a needle or machine thread 58 and a locking thread 60 around which each loop of needle thread is carried during formation of the seam. Due to the nature of a lockstitch seam and the manner of forming it, together with the diagonal cut produced by the awl, each length of thread measured by the thread finger 18 most frequently is drawn against the welt into permanent position at a slight angle to the seam line with a tendency to form a perpendicular to the 45° angle in the awl cut.

30 The usual form of seam inserted by the machine of the patents is illustrated in Fig. 11, with each length of thread exposed on the surface of the welt drawn further away from the outer edge of the welt at its left end and closer to the outer edge at its right end in successive awl cuts. The appearance of a seam thus formed is of zigzag nature, the thread lengths not being disposed in accurate alinement. In many instances a zigzag appearance is objectionable from a standpoint of style, particularly where the color of the thread is selected to contrast with that of the welt and also for structural or other reasons where low quality materials are employed in a shoe.

35 According to a feature of the present invention, the thread lengths of a seam exposed on the welt of a shoe are brought into uniformly accurate alinement with each other (Fig. 10) to form a seam having a narrow straight line appearance in which the strength, tightness, and durability are not otherwise impaired. With the use of this feature it has been found unnecessary to change the angle of cut in the awl perforation, so that existing machines and other established procedures in adjusting machines may be retained without requiring modification of accepted practices.

40 To these ends the needle opening 46 is formed at its end toward which the work is fed with a restriction 62 of insufficient width to admit the needle. The restriction is approximately equal in width to the thickness of the needle thread 58 so that the forward or rearward movement or other displacement from seam alinement of 45 the thread lengths disengaged from the thread

finger 18 and drawn toward the welt by the retracting needle is prevented or extremely limited and the position to which the measured thread lengths are drawn laterally of the seam line against the work is well defined in accurate alignment with the exposed thread lengths on the welt of previous stitches. The position of the work support with relation to the needle is adjusted to insure close spacing between the needle and the entry to the restriction, so that as each slack measured length of thread is being drawn against the welt it is confined both forwardly and rearwardly as well as at the ends of the restriction. In many instances such restriction is sufficient by itself to insure accurate alignment of thread lengths exposed on the welt of a shoe. For further characteristics of refinement in style and uniform appearance, other modifications in the shape of the work support may be found desirable.

It is frequently of advantage to accentuate the straight line appearance of the outseam in a welt shoe by reducing still further the width of the aligned thread lengths from that found with the use of the restriction 62 only. Accordingly, the upper work-engaging surface 48 of the work support at its left end may be provided with a seam alining shoulder 64 running from the needle opening 46 against which shoulder the outer side edges of the exposed thread lengths in the inserted seam are molded. The molding action of the shoulder 64 is enhanced by the forward thrust of the work support during its relative back feeding movement. This molding action on the thread lengths reduces the width of the seam and causes it to become more prominent in height.

If a still further reduction is desired in seam width, a second shoulder 66 is provided opposite the shoulder 64 with the result that a groove running from the needle opening is formed along the work engaging surface of the work support within which both side edges of the exposed thread lengths are molded toward each other. The groove 64-66 ordinarily is made with slightly narrower width than the restriction 62 but with a flaring outlet in the direction of work feed to avoid retarding the feeding movements of a shoe while sewing around abrupt curvatures, particularly about pointed toes of shoes. The shoulders 64 and 66 ordinarily merge into the upper edges of the restriction 62 without abrupt changes in dimensions, the reduction in width being made gradually and the flare at the outlet taking place smoothly so as not to produce noticeable marking on the exposed thread lengths in a seam.

To avoid an excessively high upstanding appearance in the thread lengths, the left-hand end of the work engaging surface 48 on the work support is reduced to a lower seam flattening level at 68, and the groove formed by the seam alining shoulders is terminated at the reduced work engaging surface 68 on the work support. The reduced work engaging surface 68 also is at a somewhat higher level than the lower right end of the work engaging surface 48 first engaged by the work or the bottom of the groove between the shoulders 64 and 66. With this arrangement the seam is alined by the restriction 62 and its edges molded by the shoulders or groove and as the thread lengths are carried over the surface 68 they are flattened to embed them more deeply into the substance of the work. The result in

such action is to give the seam a more nearly rectangular appearance in cross section.

Where a seam is to be sewn on a welt as close as possible to the bulging last supported surface of a shoe upper 54 within the crease between the upper and the welt, it is sometimes necessary to form the restriction in the needle opening with its forward inner surface as a continuation of the forward inner surface of the needle opening. A work support having such restriction, indicated at 70, is shown in Fig. 7, where the forward surface of the restriction is continuous with the forward surface of the needle opening, indicated at 72. Under these conditions there is little material left between the forward inner surface of the needle opening and the forward outer surface of the work support. For this reason, the forward seam alining shoulder is omitted and a rounded rear shoulder 74 is provided extending somewhat forwardly of the rearward surface of the restriction, which rearward surface is spaced from the rearward surface of the needle opening 72.

The shapes of the thread lengths emerging from the work support of the machine thus described are dependent upon the proportions of the restriction, shoulders and flattening surfaces formed thereon. For different styles of shoes, modifications in lengths of these surfaces and seam guiding elements may be made to insure the desired results, the action of each respective element being relied upon to add its own distinctive effect. Where no forward shoulder, such as illustrated at 66 in Fig. 5 is employed, it is obvious that greater pressure will be exerted on the welt nearer the outer edge of the welt on a shoe than at the rear of the seam line nearest the upper and, accordingly, the outer edge will be compressed to a greater extent than that surface inside the seam line. Such formation of the welt frequently is of advantage where cross markings later are provided on the seam in the form of indentations to give the seam a well-known "pricked up" appearance, the uncompressed inner surface of the welt receiving the markings more readily than the outer compressed surface.

Having described the invention what is claimed is:

1. A shoe outsole sewing machine having a curved hook needle, work clamping and feeding means including a presser foot at the side of the work with the needle, in combination with a work support having a needle receiving opening formed with a restriction at that end toward which the work is fed to limit the movement of the thread drawn through the work by the needle laterally of the seam line, said restriction being of insufficient width to admit the needle.

2. A shoe outsole sewing machine having a curved hook needle, work clamping and feeding means including a presser foot at the side of the work with the needle, in combination with a work support having a needle receiving opening formed with a restriction at that end toward which the work is fed to limit the movement of the thread drawn through the work by the needle laterally of the seam line, and a seam alining shoulder along the work engaging surface of the work support for molding a side edge of the seam.

3. A shoe outsole sewing machine having a curved hook needle, work clamping and feeding means including a presser foot at the side of the work with the needle, in combination with a work support having a needle receiving opening formed with a restriction at that end toward which the

work is fed to limit the movement of the thread drawn through the work by the needle laterally of the seam line, and a seam alining groove along the work engaging surface of the work support for bringing both side edges of the exposed thread lengths in successive stitches into alinement with each other.

4. A shoe outsole sewing machine having a curved hook needle, work clamping and feeding means including a carriage, a shaft on which the carriage is mounted for oscillation along the line of work feed, a work feeding support, a work clamping presser foot on the carriage and mechanism for actuating the work support and presser foot at right angles to the line of feed to cause them to exert a relatively slow rearward pull on the work during feeding movements and a relatively quick forward thrust against the work during back feeding movements, in combination with a seam alining shoulder on the work engaging surface of the work support for molding the outer edge of the seam during the forward thrust of the work support.

5. A shoe outsole sewing machine having a curved hook needle, work clamping and feeding means including a carriage, a shaft on which the carriage is mounted for oscillation along the line of work feed, a work feeding support having a needle receiving opening, a work clamping presser foot on the carriage and mechanism for actuating the work support and presser foot at right angles to the line of feed to cause them to exert a relatively slow rearward pull on the work during feeding movements and a relatively quick forward thrust against the work during back feeding movements, in combination with a restriction in the needle receiving opening of the work support at that end toward which the work is fed to limit the movement of the thread drawn through the work by the needle laterally of the seam line and to form a seam alining shoulder along the work engaging surface of the work support for molding a side edge of the seam.

6. A work support for a shoe outsole sewing machine formed with a work engaging surface, a downwardly and rearwardly swept shank and an elongated needle receiving opening intersecting the work engaging surface and extending rearwardly of the work support, in combination with a restriction at one end of the needle opening in the work support of a width approximately equal to the thickness of the sewing thread to limit the forward and rearward movements of the thread drawn against the surface of the work engaged by the work support.

7. A shoe outsole sewing machine having a

5 curved hook needle, work clamping and feeding means including a presser foot at the side of the work with the needle, in combination with a work support having a needle receiving opening formed with a restriction at that end toward which the work is fed to limit the movement of the thread drawn through the work by the needle laterally of the seam line, a seam alining shoulder along the work engaging surface of the work support at the outer side edge of the exposed thread lengths in successive stitches of a seam for bringing them into alinement with each other, and a second seam alining shoulder along the work engaging surface of the work support opposite the first-mentioned shoulder for molding the inner side edge of a seam.

8. A shoe outsole sewing machine having a curved hook needle, work clamping and feeding means including a presser foot at the side of the work with the needle, in combination with a work support having a needle receiving opening formed with a restriction at that end toward which the work is fed to limit the movement of the thread drawn through the work by the needle laterally of the seam line, and a seam flattening surface on the work support for embedding the exposed thread lengths more deeply into the substance of the work after being brought into alinement by the restriction.

9. A shoe outsole sewing machine having a curved hook needle, work clamping and feeding means including a presser foot at the side of the work with the needle, in combination with a work support having a needle receiving opening formed with a restriction at that end toward which the work is fed to limit the movement of the thread drawn through the work by the needle laterally of the seam line, and a seam flattening surface on the work support at a higher level than the end of the work engaging surface of the work support first engaged by the work for embedding the exposed thread lengths more deeply into the substance of the work after being brought into alinement by the restriction.
